(57) **CLAIM**

The ornamental design for a handle for BBQ and kitchen tongs, as shown and described.

DESCRIPTION

FIG. 1 is an elevational right-side view of a handle for BBQ and kitchen tongs, in accordance with our new design;

FIG. 2 is an elevational front-side view of the handle for BBQ and kitchen tongs of FIG. 1;

FIG. 3 is an elevational left-side view of the handle for BBQ and kitchen tongs of FIG. 1;

FIG. 4 is an elevational back-side view of the handle for BBQ and kitchen tongs of FIG. 1;

FIG. 5 is a bottom view of the handle for BBQ and kitchen tongs of FIG. 1;

FIG. 6 is a top view of the handle for BBQ and kitchen tongs of FIG. 1; and,

FIG. 7 is a perspective view of the handle for BBQ and kitchen tongs of FIG. 1.

The broken lines show environment and form no part of the claimed design.

1 Claim, 6 Drawing Sheets
